UNITED STATES PATENT OFFICE.

PHILIPP WEBER, OF VALLENDOR-ON-THE-RHINE, GERMANY.

DEVICE FOR MANUAL PRODUCING OF CIGAR FILLERS.

Application filed April 25, 1927, Serial No. 186,508, and in Germany September 12, 1925.

The present invention relates to a method and a device for manual producing of cigar fillers.

Cigars are produced either manually or 5 machinarily. In both cases the so called filler is first brought into the desired shape, whereupon it is covered by the wrapper. When producing machinarily the so called 10 pressing moulds are used, whereby the fresh fillers are torn off to the desired length and placed in a wooden mould or the like. When the mould has been filled the lid is placed upon the same and the mould is brought into the filler press. After some 15 time the mould is opened and the filler is turned, whereupon a renewed pressing takes place. The turning and repressing is necessary in order to prevent the formation of sharp edges at the seams. After drying the 20 tip and the end of the filler are shaped and loosened, whereupon the wrapper is wound round it by the cigar maker.

When producing cigars manually the so 25 called filler box is used. The fresh filler is torn off to the desired length, wrapped in paper and dried in special filler holders. Thereupon the paper is removed and the dried fillers are laid into the usual wooden 30 filler box in which it expands and takes up the desired shape. The filler is finally removed from the box and the wrapper is laid round it. This work requires much skill and dexterity from the worker, in order that waste of tobacco may be prevented.

According to the present invention the 35 filler box is arranged in such a manner, that the paper wrapper becomes superfluous and that the formation of the filler may be effected without pressure in an easy and simple way.

When producing cigars manually or 40 machinarily the filler maker by means of his sensitive faculty forms the necessary quantity of tobacco to a filler in his hand. According to the invention the filler box is arranged in such a manner that the filler expands in the same without it being necessary to apply any external pressure. Because the 45 filler worker always has the filler boxes in front of himself and because he on account of his feeling always takes the same amount of tobacco into his hand when forming a 50 filler, the size of the produced cigars will always be the same. Moreover, the filler 55 takes its form after the filler box, whereas

at known devices the filler box must follow the form of the filler.

A constructional form of the new filler box is shown by way of an example in the accompanying drawings—

Fig. 1 shows both parts of the new device.

Fig. 2 shows the assembled filler box with a portion of the same broken away.

Fig. 3 is a sectional view of the structure 65 shown in Fig. 2.

Fig. 4 shows a box support.

Fig. 5 illustrates the position of the two 70 filler box halves when the filler is laid in.

The new filler box consists of two halves 75 or moulds *a* and *b*, which, when assembled, have the form of a cigar. The moulds are preferably formed from sheet metal or the like and the interior space of the box has the size of the finished cigar filler. The 80 part *a* is equipped with a tip cap *a*¹, whereas the other part *b* forms the continuation of this cap. The part *b* is also equipped with a longitudinal sliding fold *b*¹ and is arranged in such a manner, that the joints between both box halves, when assembled, are completely flush with the inner surface of the box. One of the box parts, preferably 85 *b*, is formed with a flange or lip *c*, by means of which the box may be placed in a suitable slot *d* in the support plate *e*.

According to the shown example a list *e*¹ of wedge-shaped cross-section is fastened to a plate *e* (or the working table). The upper face of the list forms an acute angle 90 with the support plate *e*. By means of a slot or a metal band *d*¹ a pocket *d* is formed in the list, which pocket serves for taking up the flange *c* of the box.

When working, the box part *b* is fixed in 95 the slot *d* by means of the flange *c*, whereupon the member *a* is arranged in the member *b* in the manner shown in Fig. 5. Thereupon the filler worker places the prepared fresh filler in the open mould *a* resting in the mould *b* and pushes the tip into the cap *a*¹, whereupon he slowly turns the mould *a* in the mould *b*, simultaneously exerting a light pressure upon the filter, so that this 100 finally is completely surrounded by the closed, round filler box. Because the filler is fresh it is also pliable and soft. At 105 cigars having thick tips it may therefore occur, that some tobacco is pressed out through the slot between the moulds *a* and *b*, when 110

these are moved into engagement with each other. This tobacco is however pressed back into the box during the working. The filler worker now removes the closed box from the pocket d and places it for drying in a rest or clasp d^2 . Such rests are arranged on his working table in the same number as the filler boxes. The boxes may of course also be arranged in other ways than here described. The box parts a and d may also be connected to each other by means of hinges. The mode of employment illustrated in Fig. 5 is however very advantageous, because the filler with great ease can be placed in the mould.

The tip cap a^1 is especially advantageous, because it secures a uniform expansion and forming of the tip and because it allows the producing of a high-grade thoroughly aired filler, because such filler is not subjected to any substantial pressure but obtains its form by means of expansion.

The new filler box makes it possible to dispense with several working stages and to produce hand-made cigars at costs which are lower than the costs of machine produced cigars, made from the said tobacco, because the time spent by the repeated pressing procedures is saved. It must also be taken into consideration, that hand-made cigars hitherto only could be produced by highly skilled workers, whereas against such cigars by means of the new filler box may be produced also

by non-professionals, because all difficult manipulations are dispensed with and no tobacco is wasted. Further, the worker needs no longer carry the filler to and from the press, but may remain on his place during all stages of manufacture, so that also in this way loss of time and waste of material are prevented.

I claim:

1. A device for forming cigar fillers comprising two mould shaped members, which when assembled take up the form of a cigar, a tip cap on one of said members and a longitudinal sliding fold on the other of said members, both members when assembled, with the edge of one member resting in the said fold of the other member, forming a hollow mould for the filler, the joints between the two members lying flush with the interior surface of the mould.

2. A device for forming cigar fillers comprising two mould shaped members, which when assembled take up the form of a cigar, a tip cap on one of said members, a flange on the second member, a sliding fold on said second member, adapted to receive the edge of the first member and a slotted support piece receiving the flange of said second member, which when assembled with the said first member forms a continuation of the said tip cap.

In testimony whereof I affix my signature.
PHILIPP WEBER.
